UNITED STATES PATENT OFFICE

154,884

DESIGN FOR A DRESS

George Sealove, New York, N. Y.

Application January 24, 1949, Serial No. 415

Term of patent 3½ years

(Cl. D3—26)

To all whom it may concern:

Be it known that I, George Sealove, a citizen of the United States of America, residing in New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

Fig. 3 is an enlarged fragmentary view of the upper ruffle portion on the blouse portion illustrating the specific trim.

The characteristic feature of my design resides in the specific trim on the yoke and center skirt of the dress as shown.

I claim:

The ornamental design for a dress, substantially as shown and described.

GEORGE SEALOVE.
